KNURLING TOOLS

Anthony Bennett, Niles, Ill., assignor to Porto Knurling Tools, Inc., Chicago, Ill., a corporation of Illinois

Application September 20, 1952, Serial No. 310,679

4 Claims. (Cl. 80—5.1)

This invention relates to improvements in knurling tools and it consists of the matters herein illustrated and described and more particularly pointed out in the appended claims.

The invention is more particularly concerned with tools for knurling the surface of a worn bore in a work piece to "raise" the metal of said surface and provide a better fit of parts, such as a bearing, a bushing or a journal employed in the bore.

One of the objects of the invention is to provide a tool especially adapted for manual operation, in knurling the worn surface of a bore in a work piece and which tool is simple, strong and rigid in construction and is efficient in its use in "raising" the surface of bores of several different diameters and axial depths.

Another object of the invention is to provide a tool of the kind mentioned, wherein the knurls are forced into engagement with the surface of the bore by means of a wedge-like member which when turned about its axis causes the knurls to travel around and "raise" said surface.

The above mentioned objects of the invention, as well as others, along with the advantages thereof, will more fully appear as the specification proceeds.

In the drawings:

Fig. 1 is a perspective view of the two main operating parts of the tool, arranged in an axially separated position.

Fig. 2 is a horizontal sectional view through the improved tool as taken on the line 2—2 of Fig. 1, with the wedge member of the tool engaged with the inner end of the knurl carrying bars of the tool to force the knurls outwardly into operative engagement with the surface of a bore in a work piece.

Fig. 3 is a plan view of the main body member of the tool.

Fig. 4 is a vertical sectional view through the tool as taken on the line 4—4 of Fig. 2.

Fig. 5 is a top view of the wedge member of the tool.

Fig. 6 is a perspective view of one of a number of knurl carrying bars forming a part of the tool.

In general, the improved tool comprises a body assembly and a coacting wedge-like member or drift. The body has a center hole therethrough and a plurality of arcuately spaced peripheral parts separated by intermediate peripheral parts. The body also includes radial guide passageways that open at one end into the center hole and at the other end through an associated first mentioned peripheral portion. A bar is so disposed in each passageway that it may slide radially but cannot turn therein. The inner end of each bar normally extends into the center hole and the other or outer end carries a rotative knurl. Each intermediate peripheral portion is made to provide a guide arranged parallel with the axis of the hole, to adjustably receive a body supporting member that terminates at its upper end as an outwardly extending arm which engages the work piece

2

outwardly of the bore, the surface of which is to be "raised." By adjusting the arms with reference to the body, the latter may be supported at desired elevations in the bore with the knurls engaged with the surface of the bore.

These bars and the body are so correlated that there may be employed therewith some resilient means normally tending to yieldingly retract the bars relative to the passageways and at the same time limit this retraction of the bars.

The wedge-like member, which is separate from the body, may be inserted into an initial position in the center hole thereof. This member has a tapered body and a plurality of radially extending ribs which engage in recesses in the body that open into the hole and whereby when the member is turned axially causes the body to turn therewith. Parts of the tapered body of said wedge member, when in said initial position, engage the inner ends of the bars which are also tapered for engagement by said parts of the wedge member body. The top end of said wedge member has a tapping head whereby the wedge member may be further driven, as by means of a hammer, into said hole so as to extend the bars and press the knurls against the surface of the bore to be raised. This tapping head is so made as to receive a bar-like wrench and whereby said member may be turned axially and cause the body to turn therewith, with the knurls so engaged with the surface as to "raise" and renew the same.

Referring now in detail to that embodiment of the invention illustrated in the drawings, the improved tool comprises a body assembly 10 and a wedge-like member 11, the former being made up of a number of correlated parts, as will hereinafter appear, and the latter consisting of only a single part. Said body assembly and said wedge-like member appear best in Fig. 1.

The body assembly includes a main body part 12 which best appears in plan in Fig. 3. This body is of a truncated triangular shape and has a center hole 13, a plurality of arcuately spaced, concentric peripheral portions 14 and a plurality of straight intermediate peripheral portions 15, each portion 15 being diametrically opposite a peripheral portion 14. In each peripheral portion is a radial passageway 16 which opens at its outer end through said peripheral portion and opens at its inner end into the center hole 13. Each passageway is of a rectangular cross section, there being at each side of the outer end thereof an enlarging recess 17. In that part of the top of said body in the center line of a passageway 16 is an elongated opening 18 that communicates with said passageway for a purpose to appear later. On the center line of each passageway and in that side of the hole opposite the inner end of the passageway is a groove 19 that opens into the center hole. In the center part of each peripheral portion 15 is a longitudinally extending shallow groove 20 and centrally between the ends of this groove is a threaded opening 20a.

Engaged in each passageway 16 is a bar 21 which can move longitudinally but cannot turn therein and one of said bars best appears in perspective in Fig. 6. This bar, which is longer than the distance between the bore surface of the hole 13 and the associated peripheral portion 14 of the tool body, has a slightly inclined inner end surface 22 and it is bifurcated at its outer end to receive a knurl 23 that is operatively secured in place by a vertical journal pin 24. About centrally of the top surface of each bar is a recess 25, each of which receives a limit pin 26 that slides in an opening 18. A helical tension spring 27 passes around the outside of each of the limit pins and normally acts to retract them inwardly of the body until limited by the engagement of the associated pin 26 with the inner end of its slot 18.

Each groove 20 receives, for guided adjustable movement, the upright part 30 of an associated inverted L-shaped body supporting member 31, the upper end of which includes an outwardly extending arm 32, having a rounded bottom for engagement on that part of a work piece 33 about the bore 34 therein, the surface of which it is desired to raise. The upright part 30 of each supporting member 31 has a longitudinal slot 35 therein for the passage therethrough of a retaining screw 36 that threads into the associated opening 20a in the tool body. A washer 37 is disposed between said part 30 and the head of the screw so that when said screw is drawn up tight the supporting member is rigidly fixed to the body. By loosening the screws 36, the supports 31 may be adjusted upwardly or downwardly to provide the desired elevation of the body 12 in the bore 34 in an operation of the tool. The underside of each arm 32 is concaved so that it can ride on the work piece 33 without catching thereon as the tool, as a whole, is turned in an operation thereof. The spring 27 also passes around each upright part of each support 31 as best appears in Fig. 1.

When the bars 21 are in their innermost retracted positions, side portions of the associated knurl engage in the recesses 17 at the sides of the outer end of the associated passageway 16.

The wedge member 11 includes a tapering body 40 with a cylindrical upper part 41 that terminates in a top end tapping head 42 in which is formed a rectangular socket 43. This socket receives a rectangular boss on the bottom end of the body 44 of a T-shaped actuator which includes at its upper end a pair of oppositely extending, turning handles 45. Extending about the full length of the body of the wedge member, which has a taper corresponding to the angle of the inner end face 22 of the bars 21, are radially disposed ribs 46, the outer edges of which are parallel with the axis of the wedge member. These ribs are so arranged about said body as to register with the grooves 19 in the body 12 and the bottom end edges of said ribs are slightly rounded as are the bottom end corners thereof so as to pilot these ribs into said recesses in the operation of the tool. When the body assembly 10 is disposed in a bore 34 of a work piece 33, it is supported by the arms 32 of the supporting members 31, which arms then engage upon the surface of work outside and beyond the surface of the bore as best appears in Fig. 4. The bottom end of the member 11 is then inserted into the hole 13 with the ribs 46 engaged in the grooves 19 of the body and with surface parts of the smaller bottom end of the body engaged with the inner end surface of all of the bars 21. This is the initial position of the parts in a tool operation.

By means of a hammer, tapping gently on the head 42 of the wedge member, the latter is driven inwardly of the hole and because of the tapered surfaces before mentioned, the bars 21 are extended or forced outwardly to press the knurls 23 forcefully against the surface of the bore. It is pointed out that as the bars are extended outwardly, the pins 26 thereof expand the spring 27. However, the angle of taper and inclination of the surfaces of the body 40 and the inner end surfaces 22 of the bars 21 are such that the spring cannot cause the arms to retract to such an extent as to lift the wedge member out of this position.

The T-actuator is then applied to the wedge member, after which the operator grasps the handles 45 of the actuator and turns the same. By reason of the ribs 46 this turning movement of the wedge member is transmitted to the tool body assembly 10 and causes it to turn. In this turning movement of the body assembly, the knurls 23 travel about the surface of the bore and displace portions thereof which in effect raises this part of the surface. After the surface has thus been raised, the tool may be removed, after loosening the grip of

the wedge member and withdrawing the same upwardly in the hole 13.

By loosening the screws 36, the position between the body 12 and the arms 32 of the supports 31, may be altered to change the elevated position of the tool assembly in the bore for another operation, which at said different elevation, increases the area of the band of knurling formed in said surface.

Thereafter the tool is again actuated as before described.

I claim as my invention:

1. A tool for knurling the bore of a work piece embodying therein a tool body insertable into said bore and having a center hole, means operative to support said body from the work piece, a plurality of members having guided movement relative to the body inwardly and outwardly of said opening and each carrying a knurl at its outer end for operative engagement with the surface of said bore and each having an inner end disposed in said hole, said body having a plurality of recesses disposed between said members and opening into said hole, a wedge-like member for axial insertion in one direction into an initial position in said hole, said wedge-like member having a tapered body and a plurality of radial ribs, the body of the wedge-like member having parts between said ribs for engagement with the ends of said knurl carrying members and said ribs being adapted for engagement in said recesses, said wedge-like member when moved axially further into said hole operating through said parts between said ribs to extend said knurl carrying members to press said knurls against said surface of the bore, said ribs in the turning movement of the wedge-like member imparting a turning movement to the tool body to cause the knurls to travel around said surface.

2. In a portable knurling tool having a tool body with adjustable knurling elements and a combination adjusting and driving member, said member comprising a plurality of circumferentially spaced faces, said faces tapering towards one end thereof, axially extending bars separating adjacent faces, said bars projecting radially outward from the faces and a socket at one end of said member adapted to receive an actuator, whereby said faces are arranged to control adjustment of the knurling elements and said bars are arranged to drive the tool body.

3. In a portable knurling tool having a combination adjusting and driving member and a tool body, said tool body having a center hole, a plurality of outer peripheral faces, said outer faces being concentric with said center hole, a plurality of straight intermediate faces between said peripheral faces, each straight face being diametrically opposite a peripheral face, a plurality of radially extending guideways, one each communicating said center hole with an outer peripheral face, a bar slidably received in each guideway, each bar normally having one end protruding into said center hole and the other end extending outward from a peripheral face, a knurling element mounted on said other end of each bar, the very inner end of each bar adapted to engage the adjusting and driving member, means for normally urging said bars radially inward, and axially extending grooves opening into the center hole for receiving the adjusting and driving tool.

4. In a portable knurling tool having a tool body and a combination adjusting and driving member, said tool body having a center hole, a plurality of outer peripheral faces, said outer faces being concentric with said center hole, a plurality of straight intermediate faces between said peripheral faces, each straight face being diametrically opposite a peripheral face, a plurality of radially extending guideways, one each communicating said center hole with a peripheral face, a bar slidably received in each guideway, each bar normally having one end protruding into said center hole and the other end extending

outward from an outer peripheral face, a knurling element mounted on said other end of each bar, the very inner end of each bar adapted to engage the adjusting and driving member, means for normally urging said bars radially inwardly, and axially extending grooves opening into the center hole for engaging the adjusting and driving tool, said combination adjusting and driving member comprising a plurality of circumferentially spaced knurling element adjusting faces, said faces tapering towards one end of said member and adapted to engage the very inner end of said other ends of said bars, axially extending drive bars separating adjacent faces, said bars projecting radially outward from the faces and adapted to be slidably received in said grooves of the tool body and a socket at one end of said member adapted to receive an

actuator, whereby urging of said adjusting and driving member through the center hole of said tool body forces said bars radially outward and rotation of said adjusting and driving member imparts rotative driving movement to said tool body.
